Term of patent 14 years

(Cl. D61—1)

FIG. 1

FIG. 2

FIG. 3

FIG. 4

FIG. 1 is a perspective view of a camera mount for a telescope or similar article, showing my new design with the camera attachment arm in one mounting position;

FIG. 2 is an elevational view with the camera attachment arm in a second mounting position;

FIG. 3 is an elevational view with the camera attachment arm in the position shown in FIG. 1 and its swivel arms in another position;

FIG. 4 is a top plan view with the camera attachment arm in the position shown in FIG. 2.

The broken line showings of a portion of a representative telescope and a camera in FIGS. 1 and 2 are for illustrative purposes only.

I claim:

The ornamental design for a camera mount for a telescope or similar article, as shown and described.
